HOOD FASTENER

William R. Wiley, Detroit, Mich., assignor to The Bassick Company, Bridgeport, Conn., a corporation of Connecticut

Application November 11, 1931. Serial No. 574,291

16 Claims. (Cl. 292—129)

My invention relates generally to hood fasteners or hood latches, and more particularly to fasteners usable for latching automobile hoods.

5 It is an object of my invention to provide an improved hood fastener which will be operative resiliently to hold automobile hoods securely against upward vertical movement and against outward swinging, so as to prevent undesired rattling of the hood.

A further object is to provide an improved hood fastener by means of which a hood will be automatically latched when manually forced to its closed position.

15 A further object is to provide an improved hood fastener which will be automatically latched in closed position and which may be manually released from the exterior of the hood.

A further object is to provide an automatically engageable latch mechanism for automobile hoods in which the latch is mounted in a frame or housing and the latter forms a guide to facilitate engagement of the latching mechanism with the keeper.

25 A further object is to provide an improved hood fastening means which may be easily operated, which is simple in construction, and which may be economically manufactured.

Other objects will appear from the following 30 description taken in conjunction with the accompanying drawings, in which

Figure 1 is a perspective view of the inside of an automobile hood provided with my improved latching means;

35 Figure 2 is a vertical sectional view showing my improved latching mechanism in side elevation;

Figure 3 is an elevation of a portion of the exterior of the hood showing the latch releasing 40 means;

Figure 4 is an enlarged central vertical sectional view of the latch, showing the parts in latched position;

Figure 5 is a rear elevation thereof;

45 Figure 6 is a vertical sectional view thereof taken on the line 6—6 of Fig. 4;

Figure 7 is an enlarged horizontal sectional view taken on the line 7—7 of Fig. 2; and

50 Figure 8 is a central vertical sectional view similar to Fig. 4, showing the parts in unlatched position.

The fastening means of my invention is particularly adapted for use with double-hinged automobile hoods of the type commonly in use.

55 This type of hood is illustrated in Fig. 1 as com-

prising an upper portion 10 which is hinged to a central rod (not shown) which connects the radiator shell and dash board of the vehicle. The hood comprises a side plate 12 joined to the portion 10 by a hinge 14. A rod 16 forming a keeper for the latches has its forward end rigidly secured to the radiator shell 18 by means of a suitable bracket 20 and has its other end rigidly secured to the dash 22. In lieu of the rod 16, separate inverted U-shaped keepers secured to the sill 24 could be employed. The latch comprises a channel-shaped frame 26 having side-wardly bent flanges 28 and 30. Bolts 32 passing through an apertured escutcheon plate 34, through the hood plate 12 and through the suitable openings in the flanges 28 and 30 of the frame 26 firmly secure the latter to the hood side plate 12.

A latch bolt 36 is pivotally mounted between the sides of the frame 26 and has a relatively smooth- 75 ly curved edge 38 which is adapted to be engaged by the rod 16 as the latch bolt is moved downwardly relative to the rod. The latch bolt 36 is pivoted on a pin 40 riveted in the sides of the frame 26. The latch bolt has an arm 42 which is pivotally connected to a part 44 of a spring cage by means of a pin 46. The part 44 is formed from a strip of metal which is bent to substantially rectangular shape, as illustrated in Fig. 6, and forms an enclosure for the two sides and the upper end of the spring cage. The other part 48 of the spring cage is likewise formed of a bent metal strip and forms the front, rear and bottom closure of the spring cage. A compression coil spring 68 is pre-compressed between the ends of 90 the cage parts 44 and 48. It will be seen from Fig. 7 that the part 44 is guided for longitudinal sliding movement between the sides of part 48. Clockwise pivotal movement of the latch bolt 36 is prevented by the engagement of a stop surface 95 47 formed on the latch bolt with a portion 49 of the frame 26.

The part 48 has a saw-tooth-shaped projection 50 formed on its front surface which is adapted to engage the end of a sear 52. This sear has 100 a pair of outwardly projecting lugs 54 which are journaled in suitable apertures 56 formed in the sides of the frame 26. A button 58 which projects through the aperture in the escutcheon plate 34 is riveted to the lower end of the sear 105 52, a flat spring 60 being secured to the sear by means of the button. The spring 60 normally retains the sear 52 in the position shown in Fig. 4 with its upper end located beneath the projection 50. The spring 60 is not essential to the satis- 110

factory operation of the device, because the cage part 48 bears against the sear 52 at a point slightly below its pivotal axis, and will thereby tend normally to swing the sear clockwise to the 5 position in which it is shown in Fig. 4. (It will be understood that when the cage part 48 is in engagement with the cam surface 70 as shown in dotted lines in Fig. 4 the compression spring 68 tends to swing the spring cage counter-clockwise 10 about the pivot 46 because the point of contact between the cage part 48 and arm 42 of latch bolt 36 is not in direct alignment with the pivot 46.) The lower edges of the sides of the frame 26 are curved, as illustrated at 62 (Fig. 4), so as to 15 aid in guiding the latch bolt over the keeper rod 16 as the hood is moved downwardly to locked position. One or more handles 64 which are rigidly secured to the hood plate 12 are provided for manual engagement in raising and lowering 20 the hood.

In using the hood fastener of my invention it is preferable to use two latches for each side of the hood, the latches being placed adjacent the ends of the hood, as illustrated generally in 25 Fig. 1. In normal use with the hood in closed position the latch bolts 36 will engage beneath the keeper rods 16 substantially as illustrated in full lines in Fig. 4. The curved keeper engaging surface 66 of each of the latch bolts will tend 30 not only to pull the hood downwardly but also to exert a force pulling the hood inwardly against the usual stops provided on the radiator shell and dash of the automobile. This will be due to the fact that the latch bolt is normally biased to move 35 clockwise (Fig. 4) by the compression coil spring 68 which is held within the cage formed by the two parts 44 and 48.

In operation the hood is moved to its closed position by means of the handle 64. During the 40 final downward movement of the hood the curved edge 38 of each of the latch bolts will engage the keeper rod 16 and thereby be cammed inwardly (swinging the latch bolt 36 counter-clockwise, Fig. 4) until the surface 66 of the latch bolt 45 is reached. When the keeper passes the high point of the camming surface on the edge of the latch bolt 36 the latter will be swung clockwise by the spring 68 and thus pull the hood downwardly and inwardly. During this operation the 50 sear 52 will be in engagement with the projection 50 and hold the cage part 48 in its upper position.

When it is desired to release the latch bolt, the button 58 is pushed inwardly against the tension of its spring 60, thereby releasing the cage part 55 48 and permitting the latter to spring downwardly to the position shown in Fig. 8. When in this position the latch bolt is held against the keeper only by the small initial compression of the spring 68 which forces the cage part 48 downwardly 60 against the curved upper surface 70 of the latch bolt 36. This slight tension may readily be overcome by pulling the hood upwardly by means of the handle 64. When this is done the latch bolt 36 will be swung counter-clockwise to an extent 65 sufficient to permit its disengagement from the keeper rod 16. During this counter-clockwise swinging movement of the latch bolt the cage parts 44 and 48 will be moved downwardly, but in view of the engagement of the lower end of 70 the part 48 with the cam surface 70, the part 48 will not move downwardly as fast as the part 44 and the consequent relative movement of the parts 44 and 48 will cause slight additional compression of the spring 68, which compression will 75 be sufficient to return the parts to normal posi-

tion, as shown by the dotted lines in Fig. 4, and after the latch bolt has been released by pressing the button 58 and the hood wall raised sufficiently to free the latch bolt from the keeper rod 16 cause the cage part 48 to move upwardly a sufficient distance again to re-engage over the end of the sear 52.

Having thus described my invention, what I claim as new and desire to secure by Letters Patent is:

1. Fastening means for the hoods of automotive vehicles comprising a keeper fixed to the chassis of the vehicle, a housing frame secured to the hood of the vehicle, a latch bolt pivoted in said housing frame, a spring, a two-part cage enclosing said spring and maintaining it under initial compression, one of said parts being pivotally secured to said latch bolt and the other of said parts being capable of camming engagement therewith, a detent for holding said last named part from engagement with said latch bolt, and manually operable means for releasing said detent.

2. A fastener for swinging hinged hoods of automotive vehicles comprising a keeper fixed to the chassis of the vehicle, a latch bolt engageable with said keeper, a spring automatically tensioned by engagement of said latch bolt with said keeper upon moving said hood to closed position, and manually operable means for partially relieving the tension upon said spring thereby to facilitate disengagement of said latch bolt and keeper.

3. Fastening means for the hood of an automotive vehicle comprising a keeper fixed relative to the chassis of the vehicle, a latch bolt engageable with said keeper incidental to the movement of said hood to its closed position, a spring operatively associated with said latch bolt to force the latter into tight engagement with said keeper, and manually operable means for relieving the tension on said spring thereby to facilitate disengagement of said latch bolt and keeper by movement of said hood from its normal closed position.

4. A hood latch comprising a frame secured to the inside of a hood, a latch lever pivotally mounted on said frame, a spring biased normally to exert a force tending to rotate said latch lever in one direction, and manually operable means to relieve the tension of said spring.

5. Means for fastening the hoods of automotive vehicles to the chassis thereof comprising a keeper carried by one of said parts of the vehicle, a housing frame secured to the other of said parts, a latch bolt movably mounted in said housing frame, a spring, a two-piece cage enclosing said spring and maintaining it under initial compression, one of said pieces being pivotally secured to said latch bolt and the other of said pieces being capable of camming engagement therewith, a detent for holding said last named piece from engagement with said latch bolt, and manually operable means for releasing said detent.

6. A fastener for swinging hinged hoods of automotive vehicles comprising a keeper fixed to the chassis of the vehicle, a latch bolt engageable with said keeper, a spring automatically tensioned upon engagement of said latch bolt with said keeper upon moving said hood to closed position thereby to hold said latch bolt resiliently against said keeper, and means manually operable from the exterior of the hood to relieve the tension upon said spring and thereby to facili- 145 150

tate disengagement of said latch bolt and keeper.

7. Fastening means of the class described comprising a fixed keeper, a latch bolt engageable with said keeper incidental to its movement toward the latter, a spring operatively associated with said latch bolt to force the latter into tight engagement with said keeper, and manually operable means for relieving the tension on said spring thereby to facilitate disengagement of 10 said latch bolt and keeper by movement of said hood from its normal closed position.

8. A hood latch comprising a frame secured to the inside of a hood, a fixed keeper, a latch lever pivotally mounted on said frame and engageable with said keeper as said hood is moved to closed position, a spring biased by said latch lever upon its engagement with said keeper to exert a force tending to swing said latch lever in one direction, and manually operable means to 20 relieve the tension on said spring.

9. Means for fastening the hoods of automotive vehicles to the chassis thereof comprising a keeper fixed to one of said parts of the vehicle, a latch bolt pivoted upon the other of said parts of 25 the vehicle, a spring, means for stressing said spring upon moving said latch bolt toward latching position against said keeper, a detent for holding said spring stressed, and manually operable means for releasing said detent.

30 10. In a fastener for swinging hinged hoods of automotive vehicles comprising a keeper fixed to the chassis of the vehicle, a latch bolt engageable with said keeper, a compression spring tensioned upon engagement of said latch bolt with said keeper when moving said hood to closed position, and manually engageable means operable partially to relieve the tension upon said spring thereby to facilitate disengagement of said latch bolt and keeper.

40 11. Fastening means for securing the hood of an automotive vehicle to the chassis thereof comprising a keeper fixed relative to one of said parts of the vehicle, a latch bolt carried by the other part of said vehicle and engageable with said 45 keeper incidental to the movement of said hood to its closed position, a spring operatively associated with said latch bolt to force the latter into tight engagement with said keeper, sear means associated with said spring to hold one 50 end thereof against movement, and manually engageable means for moving said sear from holding position thereby to relieve the tension on said spring and to facilitate disengagement of said latch bolt and keeper upon movement of said 55 hood from its normal closed position.

12. A hood latch comprising a frame secured to the inside of a hood and having a guiding surface, a latch lever pivotally mounted on said frame, said lever having a camming surface

forming a prolongation of said guiding surface, a spring biased normally to exert a force tending to rotate said latch in one direction, and manually operable means to relieve the tension of said spring.

13. In a fastening device for securing the hoods of automotive vehicles to the chassis thereof, the combination of a keeper affixed to the chassis with a latching device affixed to the hood, said device comprising a latching bolt automatically engageable with said keeper incidental to the closing of the hood of the vehicle, resilient means for holding said latching bolt in engagement with said keeper, and manipulative means operable from the outside of the hood for relieving the compression of said resilient means to permit the opening of the hood.

14. In a device for securing the hoods of automotive vehicles to the chassis thereof, the combination of a keeper affixed to the chassis with a latching device secured to the inside of the hood, said latching device comprising a latching bolt engageable with said keeper upon moving said hood to closed position, resilient means for holding said latch in engagement with said keeper, 100 and a button projecting through said hood operable manually for relieving the compression of said resilient means.

15. In a device for securing the hoods of automotive vehicles to the chassis thereof, the combination of a housing frame connected to said hood, a bell crank shaped latch bolt pivotally connected to said frame having one arm engageable with a fixed keeper incidental to the closing of the hood, a spring cage comprising relatively movable sections, a pivotal connection between one section of said cage and the other arm of said latch bolt, a detent for holding the other section of said cage from movement, a spring in said cage for resiliently holding said first mentioned arm of said latch bolt in engagement with said keeper, and manipulative means for releasing said detent thereby partially to relieve the compression of said spring for facilitating the disengagement of said first mentioned arm from 120 said keeper.

16. A fastener for automatically securing the hoods of automotive vehicles to the chassis thereof incidental to the closing of the same, comprising a latch bolt adapted for attachment to 125 the inside of the hood and automatically engageable incidental to the closing of the hood with a keeper affixed to the chassis, means for resiliently holding said latch bolt in keeper engaging position, and means adapted to extend to the 130 outside of the hood and manually operable for relieving the tension of said resilient means.
